UNITED STATES PATENT OFFICE.

EUGENE C. RICHARD, OF DETROIT, MICHIGAN, ASSIGNOR TO SARAH L. KNEELAND, OF LANSING, MICHIGAN.

GAS OR EXPLOSION ENGINE.

SPECIFICATION forming part of Letters Patent No. 791,501, dated June 6, 1905.

Application filed December 7, 1903. Serial No. 184,190.

To all whom it may concern:

Be it known that I, EUGENE C. RICHARD, a citizen of the United States, residing in the city of Detroit, county of Wayne, State of Michigan, have invented certain new and useful Improvements in Gas or Explosion Engines, of which the following is a specification.

This invention relates to improvements in gas or explosion engines.

The objects of this invention are, first, to provide an improved vaporizer or carbureter for gas or explosion engines in which the fuel is all utilized and not wasted; second, to provide an improved vaporizer or carbureter for gas or explosion engines specially adapted for use with a throttle-governor; third, to provide an improved vaporizer or carbureter for gas-engines which is simple and compact and not likely to get out of repair.

Further objects and objects relating to structural details will definitely appear in the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

Figure 1 is a front elevation view of a structure embodying the features of my invention, 35 a portion of the fly-wheel being broken away to show the arrangement of the governor mechanism. Fig. 2 is a detail vertical sectional view taken on a line corresponding to line 2 2 of Fig. 1. Fig. 3 is an enlarged detail sectional view taken on lines 3 3 of Figs. 1, 4, and 6. Fig. 4 is an enlarged detail sectional view taken on lines 4 4 of Figs. 3 and 6. Fig. 5 is an enlarged detail sectional view taken on a line corresponding to line 5 5 of Fig. 3, showing the details of the controlling-valve *e*. Fig. 6 is an enlarged detail plan view of the vaporizer, the valve-casing *E* and the delivery-pipe *E'* being removed. Fig. 7 is an enlarged detail plan view of the gov-

ernor mechanism and its connections to the 50 valve.

In the drawings the sectional views are taken looking in the direction of the little arrows at the ends of the section-lines, and similar letters of reference refer to similar parts 55 throughout the several views.

Referring to the drawings, *A* is the frame of the base of the engine, which in this instance also serves as a storage for the liquid hydrocarbon. The crank-shaft *B* of the engine is mounted in suitable bearings *A'*. The pump *C* is connected to the storage-tank by the pipe *f*. The pump *C* is of the usual or any desired style and is provided with an upwardly-extending pump-rod *c*. A coiled 60 spring *s* is provided for returning the pump-rod to its initial position. The tension of the spring *s* is regulated by means of the collar *c''*, which is adjustably secured to the pump-rod by means of a suitable set-screw. The upper 65 end of the pump-rod *c* is arranged to engage under the end of the lever *t*, which actuates the exhaust-valve. (See Fig. 1.) The pump is actuated by the pivoted lever *b*, (see Fig. 2,) which carries a roller *b''*, adapted to engage 70 the under side of the nuts *c* on the pump-rod. These nuts are adjustable to regulate the stroke of the pump. The lever *b* is actuated by the cam *a''* on the hub of the gear *a'*. A roller *b'* rests upon the cam *a''*. The gear *a'* is driven 75 by the pinion *a* on the crank-shaft *B*. The gears *a* and *a'* are properly proportioned.

The atomizer or carbureter proper consists of a main chamber *D* and a feed-chamber *D'* therefor. A delivery-pipe *C'* connects the 85 pump to the feed-chamber. A passage *j* connects the chambers *D* *D'*. The delivery of the oil from the feed-chamber to the vaporizing or carbureting chamber is regulated by the needle-valve *i*, which is provided with a suitable knurl *i'*. The liquid hydrocarbon is delivered through the passage *j* into an oil-receptacle within the chamber *D*. This receptacle is shaped somewhat like a letter *U*, as it consists of a pair of arms or passages *j''* *j'''*, 90 connected at the bottom and open at the top. The arm or passage *j''* of the oil-receptacle opens into the mixing-chamber *x*. The pas-

sage j'' opens into or is connected to the air-passage j''' . Across the top of the chamber x is a screen e' . The screen e' is retained in position by the valve-casing E , which is 5 threaded into the top of the chamber D . The delivery-pipe E' suitably connects the chamber D to the engine-cylinder. Air is drawn through the atomizing or carbureting chamber by the suction of the engine. A valve e 10 is provided for controlling the same. (See Figs. 3 and 5.) A slanted partition plate or deflector in the bottom of the chamber D is provided to direct a considerable portion of the air passing through the carbureting-chamber into the passage j''' .

In operation air is drawn through the atomizing or vaporizing chamber by the suction of the engine, and a portion of the air passing through the passage j''' into the passages j'' 20 and j' becomes saturated with and carries or dashes the liquid hydrocarbon into the mixing-chamber x and against the screen e' , where it is met by the inrushing air, which is thereby suitably mixed therewith and drawn past 25 the valve e' into the engine-cylinder. The adjustment of the valve e regulates the amount of air drawn through the atomizer or carbureter. This adjustment is preferably automatically accomplished by means of suitable governor 30 mechanism, preferably that described in my application for a patent filed concurrently herewith, although other suitable governor means might be used. The valve e is connected by the link G' , which is secured to the arm h on 35 the shaft thereof, to the lever G , which is controlled by the governor mechanism, so that when the speed of the engine exceeds a predetermined point the governor acts upon the lever G and through its connections closes or 40 partially closes the valve, thereby shutting off from the engine a portion of the supply of carbureted air, so that the force of the explosion is decreased or the explosion is entirely prevented. The speed of the engine is thus 45 effectively regulated and this without a waste of fuel. The speed of the engine is also kept close to the predetermined rate.

An overflow-pipe f' is provided for the feed-chamber D' . This pipe extends above 50 the chamber D' a short distance and is perforated or vented at f'' . (See Fig. 4.) This arrangement keeps the oil in the chambers D and D' at about the same level.

With the parts arranged as illustrated and 55 described the liquid hydrocarbon is very effectively atomized and proper admixture with the air secured. The structure also prevents flooding of the engine. A waste of fuel is also prevented, the amount atomized being 60 equal only to the demands of the engine. The speed of the engine is kept at about the point at which it is set to run. The structure is simple and compact and is not likely to get out of repair.

65 I have illustrated and described my im-

proved vaporizer in the form preferred by me on account of simplicity and the economy of producing the same. I am, however, aware that it is capable of considerable variation in structural details without departing from my 70 invention.

Having thus described my invention, what I claim as new, and desire to secure by Letters Patent, is—

1. In an explosion-engine, the combination 75 of a storage-reservoir; a pump; suitable connections for said pump; a carbureting-chamber D connected to the engine-cylinder; a feed-chamber D' therefor, suitably connected to said pump; a delivery-passage j for said feed-chamber; a mixing-chamber in the upper portion of said carbureting-chamber D ; a U-shaped receptacle consisting of arms or passages j' j'' connected to said passage j , said passage j' opening into said mixing-chamber; 85 a screen e' across said mixing-chamber; an air-passage j''' connected to said passage j'' ; a valve above said carbureting-chamber; suitable governor mechanism; and connections for said valve to said governor, whereby said valve 90 is controlled, for the purpose specified.

2. In an explosion-engine, the combination 95 of a storage-reservoir; a pump; suitable connections for said pump; a carbureting-chamber D connected to the engine-cylinder; a feed-chamber D' therefor, suitably connected to said pump; a delivery-passage j for said feed-chamber; a mixing-chamber in the upper portion of said carbureting-chamber D ; a U-shaped receptacle consisting of arms or passages j' j'' connected to said passage j , said passage j' opening into said mixing-chamber; 100 a screen e' across said mixing-chamber; an air-passage j''' connected to said passage j'' ; for the purpose specified.

3. In an explosion-engine, the combination 105 of a storage-reservoir; a pump; suitable connections for said pump; a carbureting-chamber D connected to the engine-cylinder; a feed-chamber D' therefor, suitably connected to said pump; a delivery-passage j for said feed-chamber; a mixing-chamber in the upper portion of said carbureting-chamber D ; a U-shaped receptacle consisting of arms or passages j' j'' connected to said passage j , said 115 passage j' opening into said mixing-chamber; an air-passage j''' connected to said passage j'' ; a valve above said carbureting-chamber; suitable governor mechanism; and connections from said valve to said governor, whereby 120 said valve is controlled, for the purpose specified.

4. In an explosion-engine, the combination 125 of a storage-reservoir; a pump; suitable connections for said pump; a carbureting-chamber D connected to the engine-cylinder; a feed-chamber D' therefor, suitably connected to said pump; a delivery-passage j for said feed-chamber; a mixing-chamber in the upper portion of said carbureting-chamber D ; a U- 130

shaped receptacle consisting of arms or passages j', j'' connected to said passage j , said passage j' opening into said mixing-chamber; and an air-passage j''' connected to said passage j'' , for the purpose specified.

5. In an explosion-engine, the combination of a storage-reservoir; a carbureting-chamber connected to the engine-cylinder; a mixing-chamber in the upper portion of said carbureting-chamber; a screen across said mixing-chamber; a U-shaped receptacle connected to said storage-reservoir, one of the arms of which opens into said mixing-chamber; suitable air-ports; a valve above said carbureting-chamber; suitable governor mechanism; and connections for said valve to said governor, whereby said valve is controlled, for the purpose specified.

6. In an explosion-engine, the combination of a storage-reservoir; a carbureting-chamber connected to the engine-cylinder; a mixing-chamber in the upper portion of said carbureting-chamber; a screen across said mixing-chamber; a U-shaped receptacle connected to said storage-reservoir, one of the arms of which opens into said mixing-chamber, and suitable air-ports, for the purpose specified.

7. In an explosion-engine, the combination of a storage-reservoir; a carbureting-chamber connected to the engine-cylinder; a mixing-chamber in the upper portion of said carbureting-chamber; a U-shaped receptacle connected to said storage-chamber, one of the arms of which opens into said mixing-chamber; suitable air-ports for the other arm of said receptacle and said mixing-chamber; means for controlling said ports; a valve above said carbureting-chamber; suitable governor mechanism; and connections for said valve to said governor, whereby said valve is controlled, for the purpose specified.

8. In an explosion-engine, the combination of a storage-chamber; a carbureting-chamber connected to the engine-cylinder; a mixing-chamber in the upper portion of said carbureting-chamber; a U-shaped receptacle connected to said storage-reservoir, one of the

arms of which opens into said mixing-chamber; suitable air-ports for the other arm of said receptacle and mixing-chamber; means for controlling said ports; a valve above said carbureting-chamber; for the purpose specified.

9. In an explosion-engine, the combination of a carbureting-chamber connected to the engine-cylinder; a storage-chamber; a mixing-chamber in the upper portion of said carbureting-chamber; a U-shaped receptacle connected to said storage-reservoir, one of the arms of which opens into said mixing-chamber; suitable air-ports for the other arm of said receptacle and said mixing-chamber; a valve above said carbureting-chamber; suitable governor mechanism; and connections for said valve to said governor, whereby said valve is controlled, for the purpose specified.

10. In an explosion-engine, the combination of a storage-reservoir; a carbureting-chamber connected to the engine-cylinder; a mixing-chamber in the upper portion of said carbureting-chamber; a U-shaped receptacle connected to said storage-reservoir, one of the arms of which opens into said mixing-chamber; suitable air-ports for the other arm of said receptacle and said mixing-chamber; and a valve above said carbureting-chamber, for the purpose specified.

11. In an explosion-engine, the combination of a storage-reservoir; a carbureting-chamber connected to the engine-cylinder; a mixing-chamber in the upper portion of said carbureting-chamber; a U-shaped receptacle connected to said storage-reservoir, one of the arms of which opens into said mixing-chamber; and suitable air-ports for the other arm of said receptacle and said mixing-chamber, for the purpose specified.

In witness whereof I have hereunto set my hand in the presence of two witnesses.

EUGENE C. RICHARD.
